(57) **CLAIM**

The ornamental design for a base of night light, as shown and described.

DESCRIPTION

FIG. 1 is a perspective view of a base of night light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of FIG. 1; and,

FIG. 10 is a partial enlarged view of FIG. 4.

The broken lines in the figures are for the purposes of illustrating portions of the base of night light, which form no part of the claimed design.
